UNITED STATES PATENT OFFICE.

EMIL WESTMAN, OF MINNEAPOLIS, MINNESOTA, ASSIGNOR TO THE
ENTERPRISE MACHINE COMPANY, OF MINNEAPOLIS, MINNESOTA,
A COPARTNERSHIP.

REVERSIBLE DRIVING MECHANISM.

SPECIFICATION forming part of Letters Patent No. 787,418, dated April 18, 1905.

Application filed April 19, 1904. Serial No. 203,839.

To all whom it may concern:

Be it known that I, EMIL WESTMAN, a citizen of the United States, residing at Minneapolis, in the county of Hennepin and State 5 of Minnesota, have invented certain new and useful Improvements in Reversible Driving Mechanism; and I do hereby declare the following to be a full, clear, and exact description of the invention, such as will enable others skilled in the art to which it appertains to 10 make and use the same.

My invention relates to reversible driving-clutches, and has for its object to provide certain improvements in such a clutch with a 15 view of securing increased efficiency and durability.

To this end my invention consists of the novel devices and combinations of devices hereinafter described, and defined in the 20 claims.

The invention is illustrated in the accompanying drawings, wherein like notations refer to like parts throughout the several views.

In said drawings, Figure 1 is a view in side 25 elevation illustrating my improved clutch as applied in working position for imparting motion in either direction to the shaft at the right from a shaft turning in a constant direction located at the left--such, for example, 30 as a gas-engine shaft employed through the reversing driving-clutch to impart motion in either direction to the propeller of a boat. Fig. 2 is a view in section on the line $x^2 x^2$ of Fig. 1. Fig. 3 is a view in section on the line $x^3 x^3$ of Fig. 2 and Fig. 4. Fig. 4 is a view in section on the line $x^4 x^4$ of Fig. 3. Fig. 5 is a detail showing the relations of certain members of the reversing driving-gears. Fig. 6 is a detail showing the shipper cone or cam in 40 a different position than in Figs. 1 and 3. Fig. 7 is a view in section on the line $x^7 x^7$ of Fig. 3, but with some parts removed and others broken away, showing the right end of the clutch in the same plane as Fig. 2; and Fig. 8 45 is a section on the line $x^8 x^8$ of Fig. 3.

E represents the shaft which is driven from a gas-engine or other source of power in a constant direction, as indicated by the arrow, and

P represents the propeller or other shaft which is to be driven in either direction from 50 the shaft E through the reversible driving-clutch.

The numeral 1 represents the body or drum portion of the clutch and is provided with a cross-web 2, dividing the same into two oppositely-facing cups. The body of the clutch is also of the proper construction to afford the clutch or friction flange 3 for co-operation with the internal clamping-ring 4 and an external clamping-ring 5. The cross-web 2 of the 55 clutch-body is provided with a bearing-sleeve 10, formed integral therewith and projecting longitudinally therefrom. The left head 6 of the clutch has its hub 6^a loosely mounted on the driven shaft E. The loose drumhead 8 60 is fixed to the driven shaft P and provided with a bearing-hub 8^a with antifriction-bushing 9, on which turns the bearing-sleeve 10, projecting from the cross-web 2.

The driving-shaft E has fixed thereto a gear 70 a, and the driven shaft P has fixed thereto a relatively large gear d. Two pairs of planetary gears, marked, respectively, b and c, co-operate with the said gears a and d on the two shafts to effect the reversing-drive. The planetary gears b and c are mounted on bearing-shafts marked 7 and 7^a, respectively, which shafts are anchored to the cross-web 2 and the drum-head 6 and not only serve as the bearings for said planetary gears b and c, but also 75 serve rigidly to connect the head 6 to the body portion 1 of the clutch. The head 6 is rabbeted to fit the co-operating cup-flange of the drum. One pair of said planetary pinions b are short-faced and engage with the gear a 80 on the driving-shaft E. The other pair of said planetary pinions--to wit, the members c--are long-faced and are engaged by the short pinions b and themselves engage, respectively, 85 opposite sides of the gear d on the driven shaft. This affords the reversing-drive, as will presently be noted in tracing the action 90 of the clutch. At this place, however, it may be noted that all the planetary gears are supported within one cup of the clutch and that 95 the other members of the reversing-drive--to

wit, the gears on the two shafts—are also housed within the same cup of the clutch. It should also be noted that in virtue of their relative positions the strains on the planetary 5 gears and those delivered therefrom are balanced in respect to the actions of the shafts.

The internal ring 4 is held by a strong pin 11, fixed to and projecting inward from the head 8, and is subject to a cramping-pin 12 of 10 unequal cross-section in opposite directions and set flatwise in the opening at the split between the ends of the ring. Said cramping-pin 12 is seated in the head 8 with freedom for a rotary motion therein, but held from 15 sliding or longitudinal motion in its seat by a suitable fixed stud 13, engaging a groove 12^a in the bearing-head of the cramping-pin. To the outer end of the cramping-pin 12 is rigidly fixed a rocker-arm or cam-lever 14, having 20 an adjustable bearing-piece 15, which is subject to the cam-surface of the shipper-cone 16, mounted on the propeller-shaft P and subject to the rocking shipper-fork 17, under the control of the hand-lever 18, as best shown in 25 Figs. 1, 2, 3, and 6.

The external clamping-ring 5 is anchored at its back to some fixed base of resistance such as the block or bed casting 19, by screw-bolts 20 or otherwise, and the lower or projecting 30 jaw of its split or open ends rests on a suitable anvil or bed-block 21 at the front side of the clutch, as shown in Fig. 1. To the anvil or bed-block 21 is pivoted a strong pincer-like lever 22, provided in its short arm or 35 biting jaw with a strong set-screw 23, adapted to engage with the upper projecting jaw of the external ring 5, as best shown in Figs. 1 and 8. A link 24, attached to the hand-lever 18, is provided with a roller 25, working be- 40 tween the inclined upper face of the anvil 21 and the under surface of the long arm of the pincer-lever 22 for applying the necessary power to the external ring 5 for clamping the same tightly to the friction-flange 3 of the 45 clutch-body.

It will be noted that the studs 7 are provided with reduced ends that project through the fixed head 6 of the drum and are provided with nuts that clamp the outer surface of said 50 head and rigidly, but detachably, secure the said head to said drum. This construction is important because when the nuts are removed the head 6 may be slid upon the shaft-section E, so as to afford direct access to the gearing 55 within the drum.

The construction and relation of the parts being as above described, the action thereof may briefly be stated as follows: Let it be assumed that it is desired to turn the propeller-shaft P in the same direction as the engine-shaft E, in which instance the parts will be 60 in the position shown in Figs. 1, 3, and 8, or, otherwise stated, the external clamping-ring 5 will be free or loose, and the internal clamp-

ing-ring 4 will be tightly clamped to the inner surface of the clutch-flange 3, under the action of the cramping-pin 12, rocker-arm 14 with its bearing-piece 15, and the cam-surface of the shipper-cone 16. In this, which may be called the "normal" relation of the parts, it 65 must be obvious that the head 8 is clamped tight to the body portion 1 of the clutch by the internal clamping-ring 4, and must turn therewith under the driving action communicated through the said ring 4, and the pins 70 11 and 12. In this interlocked position of all the parts of the clutch the gears simply stand stationary and rotate with the body of the clutch and the two shafts as if the parts were all in one piece, unless there be some slip motion between the ring 4 and the clutch-flange 3, which for present purposes may be ignored. Now let it be assumed that it is desired to 75 reverse the propeller-shaft P, or drive the same in the opposite direction in respect to the rotation of the engine-shaft E. The hand-lever 18 will then be thrown rearward, thereby through the rocking shipper 17 moving the shipper-cone 16 out from under the bearing-piece 15 of the rocker-arm 14 and letting the 80 same drop off from the cam-surface of the cone down onto the shaft, as shown in Fig. 6, thereby releasing the cramping-pin 12, and permitting the internal ring 4 to assume its most contracted or normal position, free from the friction-flange 3 of the clutch-body 1. By this release it is of course obvious that the head 8 is free to 85 turn in respect to the clutch-body 1, if that should be held stationary. By said rearward movement of the hand-lever 18 the pincer-lever 100 22 is actuated through the link 24 and the roller 25, under a powerful leverage, thereby causing its short arm or jaw to tightly clamp the external ring 5 against the outer surface of the friction-flange 3 of the clutch-body and hold the 105 clutch-body stationary. Hence under the rotary motion of the engine-shaft E, assuming the same to be turning in the direction indicated by the arrow, the small gear *a* keyed thereto will turn the short-faced pinions *b* in 110 an opposite direction in respect to the gear *a*, as shown by the arrows in Fig. 4. Then from the said short-faced pinions *b* the long-faced pinions *c* will be turned in a common direction opposite to the motion of the pinions *b*, 115 as shown by the arrows, and the said long-faced pinions *c* being in mesh with the gear *d* on the propeller-shaft P will turn the same in the same direction as said short-faced pinions *b*, or, in other words, directly opposite to the 120 rotation of the engine-shaft E and its small gear *a*. When said propeller-shaft P is thus being driven reversely to the engine-shaft E under the action of the reversing train of gears within the clutch, the clutch-head 8 of course turns with the propeller-shaft P in respect to the stationary clutch-body 1, which is then being held stationary by the cramped external 125

ring 5. From a comparison of Figs. 3, 4, and 5 the relations of all the members of the reversing train of gears and of the other parts of the clutch may be readily understood, and 5 from an inspection of Figs. 3 and 4 the directions of rotation can readily be traced, as indicated by the arrows thereon.

The cross-web 2 of the clutch body or drum is cut away at its central portion to permit the 10 passage of the propeller-shaft and the hub of the large gear *d* fixed thereto. In practice a centering plug connects the abutting ends of the two shafts. When in use, the gear-cup side of the clutch is filled with hard grease and 15 the ring-cup side with oil for affording the necessary lubrication and deadening the noise.

From the foregoing description it must be obvious that this reversible driving-clutch is strong, that all the gears have large and well- 20 anchored bearings, and that the clamping-rings act on a large friction-surface and are subject to a great leverage for holding the same in their cramped or clamping positions. It should be especially noted that the bearings for the 25 clutch are so formed and related that the clutch cannot tilt in respect to either of the shafts. From the further fact that the planetary gears engage opposite sides of the gears by which they are driven and to which they impart motion it follows that the strains are balanced 30 in respect to the axes of the two shafts. This is a highly important feature toward the efficiency and durability of this form of clutch.

By actual usage I have demonstrated the 35 efficiency of the clutch herein disclosed for the purpose had in view.

While the clutch has been shown and described as applied for driving a propeller-shaft in either direction from a gas-engine shaft 40 turning in a constant direction, it will of course be understood that the clutch is capable of universal application wherever the corresponding functions are required. It will further be understood that the details of construction may 45 be modified to some extent without departing from the principle of the invention.

The "clutch-rings," so called, may of course take a great many different forms, since they are, in fact, only one of the many forms of fric-

tional clamping devices that may be used for 50 the purpose.

What I claim, and desire to secure by Letters Patent of the United States, is as follows:

1. In a reversible driving-clutch, the combination with a divided shaft, of a drum having at one end an exposed fixed head that is loose on one shaft-section and is rigidly, but detachably, secured to said drum by means extending to, and adapted to be operated from, the exterior of the drum, said drum also having a loose head that is fixed on the other shaft-section, gears mounted within said drum and connecting the two shaft-sections, and an internal and an external clamping-ring, the former being carried by said loose drumhead and 60 operating on the internal surface of said drum, and the other being anchored to a relatively fixed support, and operating on the exterior surface of said drum, substantially as described. 70

2. In a reversible driving-clutch, the combination with a divided shaft having at one end a fixed head that is loose on one shaft-section, having at its other end a loose head that is fixed on the other shaft-section, and 75 having a central web dividing it into two compartments, stud-shafts projecting from said central web, passed through the fixed head of said drum, and provided, at their outer ends, with nuts rigidly, but detachably, holding said head to said drum, gears in one compartment of said drum, certain of which are loosely mounted on said studs and others of which are carried by the abutting ends of said shaft-sections, and an inner clamping-ring and an 80 outer clamping-ring, engageable with the flange of the other compartment of said drum and working in the same plane, and which inner clamping-ring is carried by said loose drumhead, and which outer clamping-ring is 85 anchored to a fixed support, substantially as described. 90

In testimony whereof I affix my signature in presence of two witnesses.

EMIL WESTMAN.
